UNITED STATES PATENT OFFICE

HERMAN WINTER, OF BROOKLYN, N. Y., ASSIGNOR OF ONE-HALF TO THE
AMERICAN SHIP WINDLASS COMPANY OF PROVIDENCE, R. I.

HAWSE-PIPE.

SPECIFICATION forming part of Letters Patent No. 293,610, dated February 12, 1884.

Application filed June 9, 1883. (No model.)

To all whom it may concern:

Be it known that I, HERMAN WINTER, of the city of Brooklyn, county of Kings, and State of New York, have invented a new and useful Improvement in Hawse-Pipe Stoppers; and I hereby declare the following to be a full, clear, and exact description of the same, reference being had to the accompanying drawings, forming part of this specification.

10 This invention has reference to an improvement in stoppers for the hawse-pipes for ships, through which the chain or cable passes. Such hawse-pipes, both in sailing and steam vessels, extend through the bulwarks, through 15 the deck, or through the sides of vessels. In some cases the chain or cable is removed during a voyage, and in other cases anchor or other chains or cables are left in the hawse-pipes ready for immediate use. It is desirable to 20 close these hawse-pipes air and water tight, so as to prevent the entrance of either air or water, and to do this in a simple and convenient manner is the object of this invention.

The invention consists in the provision of 25 a two-part spherical stopper arranged to receive a cable or cable-chain and to fit the hawse-pipe, and provided with attachments for laterally compressing the stopper, substantially as hereinafter described.

30 Figure 1 is a sectional view of a hawse-pipe, the end of which is closed by an elastic stopper, made in two parts, so as to inclose the chain, and secured by compressing the stopper between curved glands to make an air 35 and water tight joint. Fig. 2 is a view of the same, showing the compressing-flange secured by two screw-bolts. Fig. 3 is an end view of the compressing-flange. Fig. 4 is a sectional view of the elastic stopper made in two parts, 40 so as to inclose the chain and fit the same tightly. Fig. 5 is an end view, and Fig. 6 a side view, of a hawse-pipe and a compressing-flange secured together by cams provided with sockets, into which a handspike or bar can 45 be inserted. Fig. 7 is a side view of the end of a hawse-pipe and a compressing-flange secured together by means of wedges. Fig. 8 is an end view of the same. Fig. 9 is a sectional view of part of a hawse-pipe in which

an elastic stopper is secured by compressing 50 the material in the direction of the axis of the pipe and expanding it laterally, and Fig. 10 is an end view of the same.

In the drawings, A is the hawse-pipe, provided with the flaring end *a a*. 55

B is an annular rim constructed to be secured in front of the end of the hawse-pipe A.

C is a spherical stopper, made of any suitable elastic material—such as rubber, hemp, manila—and in some cases wood will answer 60 the purpose, in which event the stopper may be covered with a packing of india-rubber or other elastic material to increase the effective action of the stopper.

D is a chain. When the chain or cable is to 65 be retained in the hawse-pipe, the stopper C is made in two parts fashioned to fit the chain and make a tight joint around the same.

E F are bolts and other devices by which the annular flange is secured to the end of 70 the hawse-pipe, so that the stopper can be compressed between the same and the hawse-pipe and a water and air tight joint secured. Various devices are shown in the drawings, and others will readily suggest themselves to 75 those skilled in the art.

The stoppers shown in Figs. 4, 5, and 9 may be secured within any hawse-pipe. As now constructed, they are made of rubber in one or two pieces. The bolts *g g* pass through the 80 same from end to end and bear on the plates *h h*. They are made of such size that they will readily enter the hawse-pipe, and are then compressed lengthwise by the bolts *g g* until the same become rigidly fixed by expanding laterally and bearing against the sides 85 of the pipe.

By the peculiar construction of the stopper any kind of hawse-pipe may be closed, so as to prevent the entrance of air or water into the 90 ship through the same.

The chain or cable may be left in the pipe, if desired, or removed, as is preferable.

Having thus described my invention, I claim as new and desire to secure by Letters Patent— 95

1. An improved hawse-pipe stopper, consisting of a two-part spherical stopper arranged to receive a cable or cable-chain and

to fit the hawse-pipe, and provided with attachments for compressing it laterally, so as to cause it to expand and engage snugly with the sides of said pipe, substantially as described.

2. The combination, with a hawse-pipe, a ring, B, and connecting-bolts E for the same,

of the spherical stopper C, made in two parts, each of which is formed with depressions to receive the chain or cable, as described.

HERMAN WINTER.
